UNITED STATES PATENT OFFICE.

LOUIS H. LOEPFE AND CHARLES M. LOEPFE, OF ST. LOUIS, MISSOURI, ASSIGNEES TO COTTONWOOD FIBER COMPANY, OF ST. LOUIS, MISSOURI, A CORPORATION OF MISSOURI.

OIL BURNER.

Application filed September 5, 1925. Serial No. 54,606.

This invention relates to oil burners.

An object of the invention is to provide an oil burner with an improved generator subjected to the heat of the burner for producing the gas from the oil, and improved means for mixing air with the gas and preventing oil from passing to the burner.

Another object of the invention is to produce an oil burner comprising a hollow generator, a tubular gas passage extending through the generator having holes opening into the generator to receive the gas therefrom, a passage leading toward the burner to conduct the gas thereto, and an air mixing device in connection with said passage between the generator and the burner.

Another object of the invention is to provide an improved oil burner embodying the structure mentioned, and a valve extending longitudinally through the gas passage that is in the generator for controlling the passage of gas therefrom.

Another object of the invention is to provide an improved oil burner in which a hollow generator surrounds and encloses a gas passage having inlet openings from the generator, and a novel construction for pumping oil to the generator for production of gas.

Other objects will appear from the following description taken in connection with the accompanying drawings, in which

Fig. 1 is a plan view of our improved oil burner in the stand in which it is supported with parts in section.

Fig. 2 is a front elevation of the oil burner in the stand, the mixing chamber between the generator and the burner being in section.

Fig. 3 is a longitudinal sectional view of the gas generator device.

Figs. 4 and 5 are cross sectional views on the lines 4-4 and 5-5, respectively, of Fig. 3.

Fig. 6 is an end elevation of the part containing the valve controlled gas outlet from the generator.

Figs. 7, 8 and 9 are sectional views on the lines 7-7, 8-8 and 9-9, respectively, of Fig. 3.

As shown the invention is supported near the bottom of a stand 1 comprising a bottom wall, end walls and a rear wall, and an open front through which the heat of the burner finds outlet.

The burner comprises a hollow member 2 having outlet openings through the upper side thereof for the gas, each of which openings is covered by a disc 3 having numerous perforations for the exit of gas. Said member also has through the inclined rear wall thereof a number of similar openings, each covered by a disc 4 having numerous perforations therethrough for the passage of gas. It will be understood that when the burner is in use the gas passes from within the member 2 through the perforated discs 3 and 4, and when ignited produces spreading flames which radiate heat that passes through the open front of the stand. The flames from the gas coming through the discs 4 play upon the generator which is thereby heated intensely, with the result that gas is generated from the oil in the generator. The member 2 is supported at one end by a connection 5 with the adjacent end wall of the stand and at the opposite end by a gas inlet pipe 6 seated upon the lower end wall of a hole through the end wall of the stand. The member 2 is further supported by a leg 7 (Fig. 2) standing upon the bottom of the stand.

The generator comprises a hollow member 8 extending parallel with and close to the wall of the member 2 through which the gas outlets through the discs 4 are provided, so that the flames from the gas coming through the discs 4 play entirely around the generator. A fitting 9 is attached to one end wall of the stand and is formed with an integral tubular extension 10 for connection with an oil supply pipe or hose. A tubular extension 11 integral with the inner side of the fitting 9 projects through the wall 1 and the end thereof encircles a closely fitting portion of a tubular part 12 which has an enlarged externally threaded inner end 13 provided with a number of longitudinal grooves 14 in its periphery constituting parts of the passages from the oil supply connection 10 to the burner. A fitting 15 is secured on the threaded outer end of the tubular part 12 and serves as a clamp to bear against the fitting 9 to clamp the parts together, as will be readily understood by reference to Fig. 3.

The generator 8 is screwed on the end of the threaded enlargement 13 so that the end thereof forms an impervious joint with the fitting 9, leaving an annular space 16 be-

5 between the tubular extension 11 and the surrounding portion of the generator 8. Oil from the oil supply connection 10 enters the annular spaces 17 around the tubular part 12 and thence passes through holes 18 to the annular space 16, and thence through the passages 14 to the gas generator.

10 A pipe 19 screws into the inner end of the enlargement 13 concentrically with the generator 8, leaving an annular space 20 into which the oil flows from the supply passages described and in which, by the heat of the burner discs 4, gas is generated.

15 A reduced threaded extension of a chamber 21 is screwed into the inner end of the generator 8. An end wall 23 for the chamber 21 is secured thereto by a nut 24 and is provided with a gas outlet opening comprising an outwardly tapering conical recess 25 and a hole 26 from the apex of the recess 25. A number of holes 27 through the wall of the pipe 19 admit the gas thereto from the generator 8. A long valve stem 28 extends longitudinally through the pipe 19, being supported at its outer end by packing by the connections 29 preventing leakage of oil and gas from the generator and burner. The valve stem 28 has threaded engagement with the connections 29 so that 20 the stem will be moved longitudinally when it is rotated. The inner end of the stem 28 has a conical portion 30 designed and arranged to seat closely within the conical recess 25 and prevents the passage of gas. A 25 needle point 31 extending from the end of the valve stem is insertable within and withdrawable from the hole 26, and such operations of the valve stem keep the hole 26 open and prevent the lodgment of carbon or 30 other deposits thereon. A triangular portion 32 on the valve stem 28 has one or more of its corners in contact with the inner surface of the wall of the pipe 19 and the hole through the adjacent portion of the chamber 35, thus supporting the valve stem properly 40 and serving to scrape portions of the inner surface of the pipe 19 to keep the passage open.

45 An air inlet connection 33 (Figs. 1 and 2) has one end supported by the nut 24 and the opposite end supporting the inner end of a pipe 34, the outer end of which is integral with and opens into the upper portion 35 of a mixer. The opening into the air 50 inlet 33 is covered by a fine mesh screen 36 shielding the gas therein from the flames of the burner and subjecting the gas to heat.

55 The lower part 37 of the mixer is clamped in connection with the upper part 35 by a bolt 38, and contacting edges of the two parts of the mixer being ground to provide an impervious joint. The pipe 6 is integral with the lower part 37 of the mixer and conducts the gas therefrom to the burners. The 60 lower part 37 of the mixer has a baffle 39

attached thereto curving inwardly and outwardly opposite the opening to the pipe 6, thus preventing a direct passage of the gas from the pipe 34 to the pipe 6, with the result that the gas and air become thoroughly 70 mixed before passing to the burner. An approximately radial flange 40 on the inner edge of the baffle 39 extends obliquely toward the opening to the pipe 6 and contributes to the mixing of the air and gas. 75

80 A screen strainer 41 (Fig. 3) within the chamber 21 prevents the passage of heavy substances and tends to maintain the apparatus in an efficiently operative condition.

85 From the foregoing it will be seen that our invention obtains all of its intended objects and purposes in a very efficient manner, may be economically manufactured and assembled and may be easily taken apart to be cleaned, repaired, or for other purposes. 85 The specific structure and relationship of the parts may be varied without departure from the nature and principle of the invention.

90 We do not restrict ourselves unessentially, but what we claim and desire to secure by Letters Patent is:—

95 1. An oil burner comprising a tubular generator, means for conducting oil into said generator, a pipe supported axially in said generator by said oil conducting means and having openings therein to receive gas from said generator, a chamber opening into said pipe to receive gas therefrom and having an outlet opening in the end opposite from said pipe, a valve stem extending through said pipe and through said opening into said chamber, and a valve supported by said stem for controlling said outlet.

100 2. An oil burner comprising a tubular generator, a pipe supported axially in said generator and having a longitudinal series of openings to receive gas from said generator, a pipe opening into one end of said generator around said first pipe, a third pipe, a chamber having an inlet opening from said first pipe and forming a communication from said first pipe to said third pipe, a valve stem extending through said first pipe and said inlet opening into said chamber, and means for holding said valve 105 stem in different adjusted positions to regulate the passage of gas from said chamber to said third pipe.

110 3. An oil burner comprising a tubular generator, a pipe supported axially in said generator and having a longitudinal series of openings to receive gas from said generator, a pipe opening into one end of said generator around said first pipe, a third pipe, a chamber having an inlet opening from said first pipe and forming a communication from said first pipe to said third pipe, a valve stem extending through said first pipe and said inlet opening into said chamber, means for holding said valve 115 stem 120 125 130

in different adjusted positions to regulate the passage of gas from said chamber to said third pipe, an oil mixing chamber in connection with said third pipe having a gas inlet and a separate gas outlet in different vertical and horizontal planes, and a baffle in said mixing chamber between said inlet and said outlet.

4. An oil burner comprising a tubular generator, a pipe extending axially through said generator and spaced therefrom and having openings therein to receive gas from said generator, a device for supporting one end of said pipe in said generator, means for conducting oil through said device into said generator around said pipe, a chamber attached to the opposite end of said generator and supporting the adjacent end of said pipe and having an opening into said pipe and a reduced gas outlet in alignment with said opening, a valve stem extending longitudinally through said pipe and through said opening to said chamber, a polygonal portion on said stem in said opening to said chamber contacting with the wall of said opening, and means for moving said stem longitudinally to open and to close said gas outlet from said chamber.

5. An oil burner comprising a tubular generator, a pipe extending axially through said generator and spaced therefrom and having openings therein to receive gas from said generator, a device for supporting one end of said pipe in said generator, means for conducting oil through said device into said generator around said pipe, a chamber attached to the opposite end of said generator and supporting the adjacent end of said pipe and having an opening into said pipe and a reduced gas outlet in alignment with said opening, a valve stem extending longitudinally through said pipe and through said opening to said chamber, a polygonal portion on said stem in said opening to said chamber contacting with the wall of said opening, means for moving said stem longitudinally to open and to close said gas outlet from said chamber, and a pointed part on the end of said valve stem movable through said gas outlet.

6. An oil burner comprising a pipe having gas inlet openings, an oil generator enclosing said pipe and having an oil inlet passage thereto at one end between said pipe and said generator, an element supporting said pipe and generator in spaced relationship adjacent to said passage, a chamber supporting the opposite ends of said generator and pipe in spaced relationship and opening into said pipe and having a gas

outlet opening in alignment with the opening into said pipe, a valve stem extending through said pipe and into said chamber, means for moving said valve stem longitudinally to open and to close said gas outlet 65 passage from said chamber, a pointed element on the end of said stem operative through said gas outlet passage from said chamber, and a polygonal portion on said stem in and contacting with the wall of said 70 opening from said chamber to said pipe.

7. An oil burner comprising a pipe having gas inlet openings, an oil generator enclosing said pipe and having an oil inlet passage thereto at one end between said pipe and said 75 generator, an element supporting said pipe and generator in spaced relationship adjacent to said passage, a chamber supporting the opposite ends of said generator and pipe in spaced relationship and opening into 80 said pipe and having a gas outlet opening in alignment with the opening into said pipe, a valve stem extending through said pipe and into said chamber, means for moving said valve stem longitudinally to open and 85 to close said gas outlet passage from said chamber, a pointed element on the end of said stem operative through said gas outlet passage from said chamber, a polygonal portion on said stem in and contacting with 90 the wall of said opening from said chamber to said pipe, and a pipe for conducting the gas from said chamber.

8. An oil burner comprising a pipe having gas inlet openings, an oil generator enclosing said pipe and having an oil inlet passage thereto at one end between said pipe and said generator, an element supporting said pipe and generator in spaced relationship adjacent to said passage, a chamber supporting the opposite ends of said generator and pipe in spaced relationship and opening into 95 said pipe and having a gas outlet opening in alignment with the opening into said pipe, a valve stem extending through said pipe and into said chamber, means for moving said valve stem longitudinally to open and to close said gas outlet passage from said chamber, a pointed element on the end of said stem operative through said gas outlet 100 passage from said chamber, a polygonal portion on said stem in and contacting with the wall of said opening from said chamber to said pipe, a pipe for conducting the gas from said chamber and provided with an opening, and a screen covering said last 105 named opening.
